ALTERNATING CURRENT BRAKING CIRCUIT

Frank W. Wendelburg and Roy J. Wadd, Milwaukee, Wis., assignors to Harnischfeger Corporation, Milwaukee, Wis., a corporation of Wisconsin

Application October 26, 1940, Serial No. 362,986

5 Claims. (Cl. 172—179)

This invention relates to an improvement in braking circuits for controlling wound rotor induction motors and is particularly well adapted to those uses where such motors are subjected to a permanently connected overhauling load, as in the case of cranes and hoists of the magnet or clam-shell type, and resides in a system wherein lowering or paying-out of the load is initiated by a preparatory movement of a controller to a preselected position at which a solenoid friction brake is released and simultaneously a moderate counter-torque opposing the lowering action of the load is exerted by the motor, whereupon the system becomes potentially responsive to uninterrupted selection of graduated degrees of high speed, regenerative lowering, or low-speed counter-torque checking of the load at the will of the operator, whereby precision spotting or high-speed runway of the load may be effected at will.

This invention is in a sense related to and constitutes an improvement over the invention disclosed and claimed in our copending application Serial No. 307,456, filed December 4, 1939, patented May 27, 1941, No. 2,243,590, in which uninterrupted transition from one type of lowering to the other is described, but in which the preparatory movement of the controller brings about an immediate high-speed lowering of the load rather than a gradual and easily controlled descent thereof, with the result that the precision of spotting obtainable by this invention is difficult of attainment.

This invention is herein described by reference to the accompanying drawing forming a part hereof wherein there is set forth by way of illustration and not of limitation one form of a circuit embodying this invention, said circuit being diagrammatically set forth therein.

In the drawing the single figure is a diagrammatic showing of a circuit embodying this invention.

The apparatus shown in the drawing will be shown by the detailed description set forth hereinafter, to be composed of a three-phase, wound rotor induction motor, the resistance of the secondary of which is selectively controllable by a conventional drum controller. In conjunction with and as a part of this controller are segments which serve to bring into action magnetic contactors which control admission of current to a magnetic friction brake and the direction of admission of current to the primary of the motor. Through these latter instrumentalities the controller is provided with an open

5 circuit center point, with a hoisting zone to the right and a counter-torque zone to the immediate left and a regenerative braking zone to the more remote left. These left-hand control zones are initially passive with the friction brake set and are rendered active only by movement of the controller to one selected counter-torque position. Thereafter the friction brake remains released and all of the several regenerative (sometimes called "running") positions as well as the counter-torque (sometimes called "plugging") positions may be immediately selected and found active. Thus, in lowering a load the friction brake becomes initially released while the motor is exerting a torque which is positively resisting the descent of the load. Inertia and this counter-torque combine to insure a very gradual starting of the downward movement of the load and if it is desired to check the lowering at once, so

10 as to "inch" the load downwardly, the same may be accomplished by a quick return of the controller to the open circuit center point position where the friction brake will become set.

On the other hand, if rapid downward travel of the load is desired, the controller handle may be moved immediately into the regenerative braking zone in a single continuous movement of the controller handle. Thus both high-speed and precision control is available to the operator in a single control handle. This is in contrast with circuits heretofore described wherein it has been necessary to initiate downward movement by a preparatory selection of a regenerative (running) position, thus positively driving the load away at the outset, making a substantial overrun inevitable, or, in contrast with circuits where "inching" must be accomplished by resort to a switch, or button, other than the controller handle.

15 20 25 30 35 40 45 50 The improved advantages indicated above are attained in this invention in the form herein described by an important but relatively simple change in the circuit of our copending application hereinabove referred to. The change consists in altering the length and position of the brake relay control segment only in the manner which clearly appears from the description which follows.

In the drawing, a three-phase wound rotor induction motor is indicated at 1. An adjustable external resistance 2 is connected as shown in the secondary circuit of the motor 1 and is provided with taps 3 leading to a controller 4 for a purpose hereinafter to be more fully described. A magnetically actuated friction brake

5 is mounted to act as shown upon the shaft of motor 1. A primary lead 7 leads directly from the motor 1 to a line connection as shown, while the primary leads 8 and 9 of motor 1 lead to the magnetic contactors 10 and 11, which together constitute a magnetically-actuated load reverser through which the sense of rotation of the primary of motor 1 may be reversed.

The magnetically-actuated brake 5 is provided with a lead 12, which is in direct connection with lead 7 and thus in permanent connection with the line. The opposite side of brake 5 is connected through a lead 13 to brake and interlock relay 14, through which line supply is derived, as shown.

Magnetic contactor 10 is arranged to admit load current to the primary of motor 1 to produce forward rotation thereof and is provided with a forward closing coil 15 arranged to act upon normally open load contactors 16 and 17 and normally closed interlock contactor 18. The magnetically-actuated contactor 11 is arranged to produce reverse rotation of the primary of motor 1 and is provided with reversed closing coil 19 arranged to act upon normally open load contactors 20 and 21, normally open interlock contactor 22, and normally closed interlock contactor 23.

Relay 14 serves to control the admission of current to brake 5 and additional purposes to be hereinafter described and is provided with relay closing coil 24, arranged to act upon normally open brake contactor 26 and normally open interlock contactors 27 and 28.

If it is assumed that motor 1 is to be applied to a hoisting or load-lifting duty, hoisting movement may be brought about by application of line supply to the primary of motor 1 through forward contactor 10 and in order to accomplish this controller current is drawn through supply lead 29 into a controller contactor finger 30, which is brought into contact with controller segments 31 arranged on the hoisting side of the controller 4, which may be moved in the well-known manner for that purpose. From segment 31 current passes through segment 32, contact finger 33, leads 34 and 35 to interlock contactor 23, which will be found closed with the controller 4 in the position now under consideration. Connection from interlock contactor 23 is then made through lead 36 with forward closing coil 15, which in turn is connected through lead 37, common return lead 38, and limit switch 39, to lead 7, which is in direct connection with the line. Forward closing coil 13 is thus energized and forward current supply is furnished to motor 1.

To provide for release of brake 5 while load current is being provided to motor 1, as above described, a controller segment 40 is provided, which comes into contact with the corresponding contactor finger 41 simultaneously with the engagement of segments 31 and 32 with their respective contactor fingers. Control current is thus supplied to lead 42, to closing coil 24 of relay 14, and from coil 24 return to the opposite line connection is made through common return lead 38, limit switch 39, and lead 7, as previously described.

With the controller 4 in any of the several selected controller-hoisting positions indicated by the letters A to H, inclusive, adjusted amounts of external resistance 2 are placed in the secondary circuit of motor 1 through cooperation of the segment group 43 with corresponding contactor fingers contained in contactor finger group 44 in the well-known manner. Upon the return of the con-

troller to the open circuit center point position, closing coil 15 becomes deenergized and contactors 16 and 17 open. At the same time closing coil 24 of relay 14 becomes deenergized and brake 5 applied. The functional characteristics of the hoisting system hereinabove detailed are quite conventional, but are derived, in part at least, through the aid of instrumentalities which are specially adapted to produce the novel functional characteristics of the lowering control which characterize this invention.

With a load in hoisted position, lowering may be brought about by relatively moving the left-hand controller segments of controller 4 toward the controller contact fingers. In the initial stages of this movement segments 45, 46, and 47 come into contact respectively with contact fingers 30, 48, and 49. During the initial stages of this movement through positions a', b' and c', nothing occurs. When movement reaches position d' the initiating stage of lowering control becomes established as follows: Line connection established through lead 29 passes through segment 45 to segment 52, which is effective in the d' position only. Connection thence continues through contact finger 41 and lead 42 to relay-closing coil 24 and thence through return lead 38 and limit switch 39 to line connection 7. As a result relay 14 moves from the normally open position to the closed position and when this occurs line supply is transmitted through contactor 26 and lead 13 to the friction brake 5, causing the same to be released.

While the above is occurring control current is also supplied to segment 46, contact finger 48, lead 50, contactor 28, lead 60 and lead 35 to contactor 23, which will be found in the normally closed position. From thence control current is supplied through the lead 36 to the closing coil 15 of the forward or hoisting switch 10 and from thence through the lead 37 and limit switch 39 back to line connection with lead 7. Line supply through the contactors 16 and 17 thus causes the motor 1 to exert a torque in the hoisting direction which is modulated by the resistance 2 at its maximum value and a very gradual descent of the load begins to take place.

The bringing of the control to position d' causes a further action to take place, namely, the establishment of a maintaining circuit for coil 24 of relay 14. This maintaining circuit may be traced from the line through conductor 29, contact finger 30, segment 45, segment 47, contact finger 49, and thence through lead 51 to contactor 27, which has been brought to the closed position as described above, and thence through leads 97 and 42 to closing coil 24, and thence back to line connection as previously described. It will thus be apparent that relay 14 will remain closed and brake 5 remain released so long as segment 47 remains in contact with contact finger 49, providing the controller has been initially moved as described above to position d'.

By reason of the described circuit relationship, segments 53 and 46 may be brought, at the will of the operator, into contact with their respective contact fingers to produce in positions a', b', c' and d' regulated degrees of counter-torque braking through circuit connections which have already been described and to positions e', f', g' and h' to produce regulated degrees or regenerative lowering in the manner about to be described.

Regenerative lowering is brought about in positions e' to h', inclusive, when control supply en-

the load at arbitrary predetermined or at selected speeds. Gradual lowering of the load is caused by the regeneration line to synchronous motor 10 passing through segment 53 passes through lead 55, normally closed contactor 18 and lead 56 to closing coil 19 of reverse or regenerative switch 11. From coil 19 direct return to the line is provided through lead 57 so that in case of over-running 15 and opening of limit switch 39 lowering can nevertheless be effected. The energizing of coil 19 causes the closing of contactors 20 and 21, causing the motor 1 to be driven in the reverse direction. Regulated amounts of resistance 2 are controlled by the control segments of group 58 and various lowering speeds at speeds in excess of synchronous speed are thus brought about.

It will be observed that once the lowering action has been initiated through engagement of the short segment 52 with its respective contact finger 41 that the operator is free to alternate at will between regenerative and counter-torque lowering, or to bring the descending load to a complete stop by movement of the controller to the open circuit center point where the brake 5 becomes applied. It will thus be apparent that the controller may be moved, if desired, to position *d'* and then immediately back to the "off" position, with the result that the load will descend a very small amount without appreciable over-running, or may be returned from position *d'* to the "off" position gradually, resulting in a very slow descent of the load, which may be checked or stopped with great precision. On the other hand, if a speedy dropping of the load is desired, the controller may be moved without interruption into one of the positions *e'* to *h'*, inclusive, where the rapid descent characteristic of supersynchronous regenerative braking is obtained, at the end of which rapid drop, the cushioning restraint of counter-torque braking may be resorted to before the "off" position and the application of brake 5 occurs.

It will thus be apparent that an improved control has been provided, having all of the versatility of controls heretofore proposed and having in addition the distinctly advantageous characteristic of being able to produce a small downward movement of the load without substantial overrunning.

It is intended that the protection of Letters Patent to be granted hereon be not unnecessarily limited by the illustrative example set forth hereinabove, but that the same shall extend to the limits of the inventive advance disclosed herein as set forth in the claims hereto appended.

That which we claim as our invention is as follows:

1. In a braking control system for wound rotor induction motors, the combination comprising a motor, a brake, a movable controller, said controller being provided with an "off" position, a zone for graduated degrees of counter-torque braking extending from said "off" position with the position of least counter-torque at the end of said zone remote from the "off" position and an adjacent zone for regenerative braking disposed at the remote end of said counter-torque zone, a switch responsive to connect said motor for counter-torque braking only after movement of said controller from the "off" position to the remote end of said counter-torque zone, a second switch rendered active only upon movement of said controller to said remote end of said counter-torque zone for causing release of said brake, means responsive to movement of said controller into said regenerative zone for connecting said motor for regenerative braking, and means in conjunction with said controller for maintaining

counter-torque braking only after movement of said controller to said remote end of said counter-torque zone and until said controller is moved to the "off" position.

2. In a braking control system for wound rotor induction motors, the combination comprising a motor, a brake, a movable controller, said controller being provided with an "off" position, a zone for counter-torque braking and an adjacent zone for regenerative braking, a switch responsive to connect said motor for counter-torque braking only after movement of said controller to a preselected position in said counter-torque zone, a second switch rendered active only upon movement of said controller to said preselected position for causing release of said brake and for completing the circuit by which said first-mentioned switch responds, means responsive to movement of said controller into said regenerative zone for connecting said motor for regenerative braking, and means in conjunction with said controller for maintaining said brake in released position after releasing the same and until said controller is moved to the "off" position.

3. In a braking control system for wound rotor induction motors, the combination comprising a motor, a brake, a movable controller, said controller being provided with an "off" position, a zone for graduated degrees of counter-torque braking extending from said "off" position with the position of least counter-torque at the end of said zone remote from the "off" position and an adjacent zone for graduated degrees of regenerative braking extending from said remote end of said counter-torque zone, a switch responsive to connect said motor for counter-torque braking only after movement of said controller from the "off" position to the remote end of said counter-torque zone, a second switch rendered active only upon movement of said controller to said remote end of said counter-torque zone for causing release of said brake, means responsive to movement of said controller into said regenerative zone for connecting said motor for regenerative braking, and means in conjunction with said controller for maintaining said brake in released position and for preserving active all of said positions of braking after movement of said controller to said remote end of said counter-torque zone and until said controller is moved to the "off" position.

4. In a braking control system for wound rotor induction motors, the combination comprising a motor, a brake, a movable controller, said controller being provided with an "off" position, a counter-torque position, and an adjacent regenerative position, a switch responsive to connect said motor for counter-torque braking upon movement of said controller to said counter-torque position, a second switch rendered active upon movement of said controller to said counter-torque position for causing release of said brake and for completing the circuit by which said first-mentioned switch responds, means responsive to movement of said controller into said regenerative position for connecting said motor for regenerative braking, and means in conjunction with said controller for maintaining said brake in released position after movement to said counter-torque position and until said controller is moved to the "off" position.

5. In a control for a hoisting motor of the wound rotor induction type, the combination

comprising a motor, a brake, a movable controller, said controller being provided with a hoisting zone, an "off" position adjacent said hoisting zone, a zone for graduated degrees of counter-torque braking adjacent said "off" position, and a zone for graduated degrees of regenerative braking adjacent said counter-torque zone, a switch responsive to connect said motor for hoisting upon movement of said controller into said hoisting zone, a limit switch for rendering said first-mentioned switch inoperative after predetermined travel of said motor in a hoisting direction, said first-mentioned switch being also responsive to connect said motor for counter-torque braking only after movement of said controller to the "off" position.

troller to a preselected position in said counter-torque zone, a third switch rendered active only upon movement of said controller to said preselected position for causing release of said brake, means independent of said limit switch responsive to movement of said controller into said regenerative zone for connecting said motor for regenerative braking, and means in conjunction with said controller for maintaining said brake in released position after movement of said controller to said preselected position and until said controller is moved to the "off" position.
